UNITED STATES PATENT OFFICE

EMIL E. KUNTZSCH, OF ST. LOUIS, MISSOURI

SMOKE ABATER AND SOOT REMOVER

Application filed October 16, 1928. Serial No. 312,893.

This invention relates to a smoke consumer, and more especially to the class of smoke abaters and soot removers.

The primary object of the invention is the provision of a machine of this character, wherein the same is attached and coacts with the outlet or smoke flue of a furnace or the like, and when in operation, will automatically effect the consumption of smoke or the abatement thereof, and the removal of soot from the flue, thus avoiding the belching of smoke from the chimney or stack, during the working of the furnace, and also avoiding the accumulation of soot within the flue, thereby eliminating the cleaning of the chimney from the constant use of the furnace.

Another object of the invention is the provision of a machine of this character, wherein on the starting thereof, the damper within the flue of the furnace, which is normally open, will be initially, manually closed, so that the spent products of combustion will be diverted from the flue through the machine, for the filtering of the same, to abate or remove smoke and other foreign matter, particularly soot, and when the machine is stopped, the damper or flue will be automatically opened, thereby eliminating manual re-opening of such damper or flue.

A further object of the invention is the provision of a machine of this character, wherein the construction thereof is novel in form, and when in operation, will abate or cause the elimination of smoke issuing from the flue of a furnace or chimney, and at the same time, will maintain said chimney of flue free from soot and foreign matter.

A still further object of the invention is the provision of a machine of this character, which is comparatively simple in its construction, readily and easily attached to the flue of a furnace or the like, thoroughly reliable and efficient in its purpose, strong, durable and inexpensive to manufacture and install.

With these and other objects in view, the invention consists in the features of construction, combination and arrangement of parts, as will be hereinafter more fully described, in detail, illustrated in the accompanying drawings, showing the preferred embodiment of

the invention, and pointed out in the claims hereunto appended. It is of course to be understood that changes, variation and modifications may be made in the invention, as come properly within the scope of the appended claims, without diverting from the spirit of the invention or sacrificing any of its advantages.

In the accompanying drawings,

Fig. 1 is a perspective view fragmentarily disclosing a smoke flue of a furnace, and a machine constructed in accordance with the invention, applied thereto.

Fig. 2 is a view similar to Fig. 1, showing in detail, the adjunct parts of the machine.

Fig. 3 is a top plan view of the machine, parts thereof being broken away for the sake of clearness of certain parts of said machine.

Fig. 4 is a sectional view on the line 4—4 of Fig. 3, looking in the direction of the arrows.

Fig. 5 is a sectional view on the line 5—5 of Fig. 3, looking in the direction of the arrows.

Fig. 6 is a fragmentary vertical transverse sectional view, taken approximately on the line 6—6 of Fig. 4.

Fig. 7 is a fragmentary elevation of the flue of the furnace, showing by dotted lines the closed position of its damper and the position of the parts controlling said damper.

Similar reference characters indicate similar parts throughout the several views in the drawings.

Referring to the drawings in detail, A designates generally a portion of the smoke or spent products of combustion flue of a furnace, which may be of any ordinary construction, and has arranged therein a swinging damper B, which is normally open, the damper being pivotally supported centrally within the flue A.

Adapted to be attached to the flue A is the smoke abater or consumer, and soot remover, which comprises a box-like tank 10, supported upon uprights or legs 11, at the lower corners thereof, so that said tank can rest, upon and elevated from, a foundation. The interior of the tank is suitably lined to provide a water reservoir 12 for containing a body of water 13, maintained at a predetermined level through a float actuated valve

14, controlling a water inlet 15, leading from a storage or supply tank 16. The inlet 15 has a hose connection 17 with a faucet 18 tapped in the storage or supply tank 16, the faucet being provided with the manually operable valve 19, so that the supply to the reservoir 12 from the tank 16 can be cut off at will.

Rotatably arranged within the reservoir 10 12 is a cylindrical foraminous filter or screen 20, the axle 21 of which is journaled in the sides of the tank 10, and overhanging this filter or screen 20 from the top of the tank 10, is a baffle 22 which prevents smoke entering 15 the tank at one side of said filter or screen from escaping to the other side thereof, except by passage through the filter or screen. Provided in opposite ends of the tank 10, contiguous to its bottom, are drain openings 23, 20 each being closed by a removable plug 24, and the removal of this plug permits the draining of the reservoir 12, as will be obvious.

Supported at one side of the tank 10, above its top, is a table 25, the supports of the latter being brackets 26, suitably secured to the tank. Upon this table 25, is secured an electric motor 27, its drive shaft 28 being provided with a worm screw 29, meshing with a driven worm gear 30, the same being equipped 30 to constitute a pulley for a belt 31, which is engaged with a pulley 32, fixed to the axle 21 of the filter or screen 20, and in this manner, motion from the motor 27 is transmitted to the said filter or screen for rotation thereof.

35 Axially in alignment with the drive shaft 28 of the motor 27, and spaced therefrom, is a fan casing 33 having therein a fan, not shown, operated directly from said shaft 28, and this casing 33 has its intake pipe 34 communicating with the flue A of the furnace, while its peripheral outlet pipe 35 opens into the tank 10 at one side of the filter or screen 20, while leading from said tank 10, at the other side of the filter screen 20 is an exhaust 40 or outlet pipe 36, which opens into the flue A at a point beyond the damper B therein, the intake 34 of the fan casing 33 being located at the other side of said damper, or next to the furnace head.

50 Connected with the pivot of the damper B is a weighted arm 37, this being located exteriorly of the flue A, and its weight 38 is formed with a crank 39, pivotally engaged in a coupling 40, fixed to a propping element 55 41, the latter slidably maintained upon a swinging terminal arm 42 of a rocking shaft 43, supported in a bearing bracket 44 Fig. 3 fixed to the bearing 47 Fig. 2 of the drive shaft 28 of the motor 27, the shaft 43 at its 60 other end being formed with a crank 48 pivotally engaged in a sliding trip 49, supported upon a swinging runway or guide 50, which is hinged at 51 to a fixed hanger 52 therefor.

At one side of the slide trip 49 is supported 65 a releasing latch 53, the same being adapted

for engagement in a notch 54 in the sliding trip 49, to maintain it normally against movement, and in this normal position, the damper B will be closed in the flue A.

Suitably supported upon the drive shaft 70 28 of the motor, is a governor 55 having a series of weighted centrifugally actuated arms 56, these when normally at rest, which is the contracted relation thereof, being in the path of the latch 53, so that said latch 53 75 will be operated to release the trip 49, thereby permitting the damper B, when closed, to become automatically open. The arms 56 of the governor 55, when the motor is traveling at proper speed for the actuation of the 80 fan 33 and the filter screen 20, will be out of the path of the latch 53, so that it will be undisturbed by the governor, and is only operated when the governor arms 56 are contracted or at rest position.

85 Normally, as has been stated, the damper B in the flue A of the furnace, is normally open, and in this position, the weight 38 is lowered (herefore to counter-act the weight, and to shift the damper B to closed position 90 it is necessary for an attendant, prior to the starting of the motor 27 for the operation of the machine hereinbefore described, to manually shift the trip 49 to the position shown in Fig. 7 of the drawings, whence the 95 latch 53 will engage the trip 49 to lock it in such position. This movement of the trip 49 transmits motion through the crank terminal 48 of the shaft 43 to the terminal arm 42, causing it to raise and through the 100 element 41 and coupling 40 therewith, the crank 39 of the weight 38 will effect the raising of said weight and through its connection 37 with the pivot of the damper B, the latter will become turned to closed position 105 in the flue A. Now, on the starting of the motor 27, the arms 56 of the governor 55 will instantly swing from rest position outwardly, thereby clearing the path of the latch 53 to be ineffective thereon. The motor 27 started, the fan operates drawing the 110 spent products of combustion from the flue A into the reservoir 12, whence the spent products will be filtered through the filter or screen 20, removing smoke therefrom and 115 subsequently exhausted or delivered through the outlet 36, back into the flue A, beyond the closed damper point thereof, to be discharged from said flue or chimney that may be attached thereto.

120 When the motor is stopped, the governor arms 56 will come to rest or in contracted position, and just prior to the stopping of said motor, these arms 56 in the position named, will act upon the latch 53, releasing it, whereupon the trip 49 will be caused to lower under the influence of the weight 38, and this influence of the weight swings the damper B to open position automatically, which is the normal position of the damper. 125 130

The level of the water in the tank 10 is automatically controlled by the float actuated valve 14, which will be clearly obvious, so that a portion of the filter or screen 20 will be immersed. As the filter or screen 20 rotates, a screen of water thereon will be effected within the tank 10 for action upon the smoke admitted thereto, to eliminate the same from the flue A, and the formation of soot therein.

10 What is claimed is:

1. In a smoke consumer or abater of the character described, comprising a water containing reservoir having a smoke screen means therein, mechanism for conveying smoke from a furnace flue into the reservoir at one side of the screening means, an outlet connection at the other side of the screening means from the reservoir to said flue, a 15 motor for actuating the screening means, a damper within the flue between the points of communication of the reservoir therewith, normally open and manually initially closed, and governor operated mechanism controlled 20 by the motor for effecting the opening of the damper after being manually initially closed, and when the motor is being rendered passive.

2. In a smoke consumer or abater of the character described, comprising a water containing reservoir having a smoke screen means therein, mechanism for conveying smoke from a furnace flue into the reservoir at one side of the screening means, an outlet connection at the other side of the screening means from the reservoir to said flue, a motor for actuating the screening means, a damper within the flue between the points of communication of the reservoir therewith, normally open and manually initially closed, governor operated mechanism controlled by the motor for effecting the opening of the damper after being manually initially closed and when the motor is being rendered passive, water supply means for the reservoir, and means for maintaining a predetermined level of water within said reservoir.

3. In a smoke consumer or abater, comprising a tank forming a water reservoir, means for supplying water thereto, means for maintaining a predetermined level of water therein, a foraminous rotatable filter within the reservoir and partly immersed in the water, inlet and outlet connections between the reservoir and a smoke flue of a furnace, said connections opening into the reservoir on opposite sides of the filter and 45 at distant points in the flue, a suction fan arranged in the inlet connection, a motor operating the fan and filter, an opening and closing damper adapted to be located in the furnace flue, and mechanism operable by said 50 motor for automatically effecting the open-

ing of the damper when closed, and active on the shutting off of the motor.

4. In a smoke consumer or abater, comprising smoke eliminating mechanism adapted to be connected with a furnace flue, a 70 damper operable in the flue to direct the contents thereof through said mechanism, and mechanism automatically operable on the arresting of the smoke eliminating mechanism to adjust said damper to direct the contents 75 of the flue therethrough.

5. In a smoke consumer or abater, a smoke eliminating mechanism having a movable filter, means adapted to be located in a furnace flue for diverting smoke therefrom to the filter, a suction element in the communication between the flue and smoke eliminating mechanism, a motor for operating the filter and suction element, said means within the flue to permit the spent products of combustion of a furnace to pass directly therethrough or through the smoke eliminating mechanism, and mechanism under the control of the motor operable upon said last named means to permit the direct passage of the products of combustion through the flue when said motor is rendered inactive.

In testimony whereof I hereunto affix my signature.
